UNITED STATES PATENT OFFICE.

JOHN HAM, OF BROOKLYN, NEW YORK, ASSIGNOR TO THE HAM COAL SAVING COMPANY, OF NEW YORK.

STEAM-BOILER FURNACE.

SPECIFICATION forming part of Letters Patent No. 360,385, dated March 29, 1887.

Application filed December 17, 1885. Renewed August 26, 1886. Serial No. 211,942. (No model.)

To all whom it may concern:

Be it known that I, JOHN HAM, a citizen of the United States, residing at Brooklyn, in the county of Kings and State of New York, have 5 invented new and useful Improvements in Steam-Boiler Furnaces, of which the following is a specification.

This invention relates to certain improvements on the devices described in Letters Patent No. 331,635 granted to me December 1, 1885, and has for its object to render said devices applicable to tubular steam-boilers with metallic fire-boxes—such, for instance, as locomotive-boilers.

15 The peculiar and novel construction of the device which constitutes my present invention is pointed out in the following specification and claims, and illustrated in the accompanying drawings, in which—

20 Figure 1 represents a transverse vertical section of a locomotive-boiler in the plane xx , Fig. 2. Fig. 2 is a longitudinal vertical section in the plane yy , Fig. 1. Fig. 3 is a sectional end view of the air-distributer on a 25 larger scale than the previous figures. Fig. 4 is a longitudinal section of the same.

Similar letters indicate corresponding parts.

In the drawings, the letter A designates the shell of a locomotive-boiler. B is the fire-box; 30 C, the smoke-box, and E E are the fire-tubes.

In the interior of the fire-box is situated the air-distributer F, the front end of which rests upon a bracket, G, secured to the inside of the front wall of said fire-box, while the rear 35 end of said air-distributer is supported by one or more air-supply pipes, E*. For this purpose two or more of the fire-tubes are made to extend a sufficient distance beyond the rear wall of the fire-box and into the rear end of

40 the air-distributer, and in order to produce a convenient connection between the air-distributer and the air-supply pipes I use a cap, H, the cover of which is perforated to admit the ends of the air-supply pipes, and which is provided with a flange, a, (best seen in Figs. 3 and 4,) which is perforated for screw-bolts b, by means of which it can be readily secured to the inner end of the air-distributer. The bracket G is concave, (see Fig. 3,) and the outer end 45 of the air-distributer rests loosely on the same,

so that said air-distributer can expand and contract by the changes of the temperature to which it is subjected. At the same time the concave bracket retains the end of the air-distributer against the jar of the locomotive. 55 When the bolts b are unscrewed, the air-distributer can be readily removed.

The outer ends of the air-supply pipes E* extend into the smoke-box C, and they are connected to an air-box, I, from which extends the 60 air-funnel K. This air-funnel extends up through the top of the smoke-box on the side of the smoke stack, and it is provided with a bell-shaped mouth-piece, so that when the locomotive moves forward a quantity of atmospheric air passes through the air-supply pipes into the air-distributer, whence it escapes through a large number of perforations for the purpose of producing combustion of the unconsumed gases which rise from the fire in the 65 fire-box. The air-funnel K may be connected to the air-box I in such a manner that it can be swiveled round, in order to catch the air when the locomotive moves in a backward direction. In the air-funnel is placed a valve, 70 75 c, which can be adjusted from the engineer's cab by means of a rod, d, so as to regulate the quantity of air admitted to the air-distributer.

In practice I propose to place two air-distributers into the fire-box, one on each side, 80 so that a sufficient quantity of air may be introduced to produce complete combustion of the unconsumed gases which rise from the fire in the fire-box, and since the air-supply pipes E* extend through the boiler the air on reaching the air-distributer is heated to such a degree that it is not liable to cool off the temperature in the fire-box. 85

What I claim as new, and desire to secure by Letters Patent, is—

1. The combination, with a tubular steam-boiler and its metallic fire-box, of a bracket attached to the inner side of the front wall of the fire-box, one or more air-supply pipes extending through the boiler and terminating in front 95 of the boiler, and a perforated air-distributer supported at its front end by the bracket and at its rear by the projecting ends of the air-supply pipe or pipes, said distributer being located in the top part of the fire-box between 100

the tube-sheet of the boiler and the front wall of the fire-box, substantially as described.

2. The combination, with a tubular steam-boiler and its metallic fire-box, of a bracket attached to the inside of the front wall of the fire-box, one or more air-supply pipes extending through the boiler and terminating in front thereof, and a perforated air-distributer supported at its rear end by said air-supply pipe or pipes and loosely resting at its front end on the bracket without rigid connection therewith, so as to expand and contract longitudinally without breakage of its support, substantially as described.

15 3. The combination, with a tubular steam-boiler and with its metallic fire box, of a bracket secured to the inside of the front wall of the fire-box, one or more air-supply pipes extending through the boiler, a cap secured to the inner ends of the air-supply pipes, and an air-distributer supported at its front end by the bracket and secured at its rear end to the cap, substantially as shown and described.

4. The combination, with a tubular steam-boiler having a metallic fire-box, B, at one end and a smoke-box, C, at the other end, of air-supply pipes extending through the boiler and projecting from each end thereof, the perforated distributer located wholly within the upper part of the fire-box, between the front wall thereof and the tube-sheet of the boiler, and loosely supported at its front end and con-

nected directly at its rear end with and supported by the air-supply pipes, an air-box located in the said smoke-box and connected directly with the air-supply pipes, and an air-funnel extending from the air-box, substantially as described.

5. The combination, with a tubular steam-boiler having a fire-box, B, at one end and a smoke-box, C, at the other end, of a series of air-supply pipes extending through the boiler and projecting from each end thereof, the perforated distributer located wholly within the upper part of the fire-box, between the front wall thereof and the tube-sheet of the boiler, and loosely supported at its front end and connected at its rear end with and supported by the air-supply pipes, an air-box located in the smoke-box and connected directly with the air-supply pipes, an air-funnel extending from the air-box, a valve located in the air-funnel, and a rod connected with the valve and arranged to extend to the engineer's cab for adjusting the valve to control the supply of air to the air-box and air-distributer, substantially as described.

In testimony whereof I have hereunto set my hand and seal in the presence of two subscribing witnesses.

JOHN HAM. [L. S.]
